UNITED STATES PATENT OFFICE.

HENRY VAN HOEVENBERGH, OF BROOKLYN, NEW YORK.

IMPROVEMENT IN TELEGRAPH APPARATUS.

Specification forming part of Letters Patent No. 147,352, dated February 10, 1874; application filed August 16, 1873.

To all whom it may concern:

Be it known that I, HENRY VAN HOEVENBERGH, of Brooklyn, in the county of Kings and State of New York, have invented an Improvement in Telegraphic Call-Instruments, of which the following is a specification:

When a permanent magnet is in contact with the cores of an electro-magnet, said cores are magnetized by induction, and the electric condition of said cores and the surrounding helices is so changed that if the contact between the permanent magnet and the cores is suddenly broken there will be a pulsation sent through the circuit of which the helices form part.

I avail of this electric operation to operate a call-instrument at a distant station, by making the helices of an electro-magnet at the distant station part of the circuit of the electro-magnet that is energized by the permanent magnet, and I construct the mechanism of the call-instrument with reference to operating with a sudden feeble current, such as that induced in the foregoing manner.

In the drawing, Figure 1 is a plan of the magnet at the one station, and Fig. 2 is an elevation of the call-instrument at the other station.

The permanent magnet *a* is set to swing on the fulcrum *b*, and is provided with a handle or knob, *c*, which also should be fitted with an adjusting-screw to regulate the extent of motion. *e e* are the cores, around which are wound the helices *f f*, that are connected with the line-wires or line and earth to the distant station, and at the call-instrument the helices of the electro-magnet *h* are in the metallic circuit, and said magnet *h* is energized by suddenly separating *a* and *e*. The sudden contact of *a* and *e* will also send a pulsation to *h*; but it is preferable to close gradually, so as not to induce a sudden secondary current and depend upon breaking the contact between *a* and *e* suddenly to operate the distant instrument. The armature *k* of the magnet *h* should be balanced so as to move freely, and it is preferable to employ a clock movement to actu-

ate the hammer *l* and strike the bell *m*. The clock movement *n* is of any desired character, and rotates the cam-wheel *o*, and this cam-wheel serves to set the armature *k*, and the armature becomes a stop to the clock-work. Two fingers, *r*, upon an arm from the armature *k* are made with an opening between them for the edge of the cam-wheel *o*, and this cam-wheel *o* is cut open at one place with a mouth wide enough to allow one of the fingers to pass through, and such wheel is bent at one side of the mouth to form a cam, as represented in Fig. 3, so that when the armature is attracted by the electro-magnet *h*, the fingers are moved and allow the disk or wheel *o* to rotate between them, and at this time the call is sounded, and in the latter portion of the revolution of the wheel *o* the cam moves the fingers *r* into the position shown in Fig. 3, to stop the further rotation of the cam-wheel.

I do not claim an electro-magnet attached to a permanent magnet in which the cores of the electro-magnet are energized by induction, and a movable armature used to break contact with the cores and incite a current in the helices. In this case the cores remain magnetic by induction. In my instrument the cores and permanent magnet are separated, thereby increasing the action in the coil by the discharge of the magnetism of the cores.

I claim as my invention—

1. The permanent magnet *e*, set to swing upon the fulcrum *b*, and movable by the handle or knob, in combination with an electro-magnet, the cores of which are magnetized by induction, and from which the permanent magnet is separated by the movement thereof, substantially as set forth.

2. The cam-wheel *o*, fingers *r r*, and armature *k*, in combination with the electro-magnet *h*, clock-work *n*, hammer *l*, and bell *m*, substantially as and for the purposes set forth.

Signed by me this 9th day of August, 1873.
HENRY VAN HOEVENBERGH.
